UNITED STATES PATENT OFFICE.

CHARLES HAMMEN, OF CHICAGO, ILLINOIS, ASSIGNOR OF ONE-HALF TO
JOSEPH MOHR, OF CHICAGO, ILLINOIS.

VALVE-GEAR.

No. 833,164.

Specification of Letters Patent.

Patented Oct. 16, 1906.

Application filed January 11, 1905. Serial No. 240,617.

To all whom it may concern:

Be it known that I, CHARLES HAMMEN, a citizen of the United States, residing at Chicago, in the county of Cook and State of Illinois, have invented certain new and useful Improvements in Valve - Gears for Fluid-Pressure Motors, of which the following is a specification.

This invention relates to valve-gears for fluid-pressure engines, having special application to engines of the marine and locomotive types, wherein the direction of motion of the engine is principally in one direction.

The invention has for its principal object to increase the efficiency of such engines, and this object is accomplished through the provision of an apparatus whereby the range of application of the link-motion as a variable-expansion gear is increased. The common way of using the link or other reversing valve-gear of steam-engines to effect variable expansion is objectionable when cutting off earlier than five-eighths of the stroke on account of the premature release and compression resultant therefrom. I have found that by using two eccentric-pins in the link-block instead of but one and connecting these to two valves or sets of valves in the engine and providing the same with sufficient steam and exhaust lap, respectively, to effect simultaneous cut off and simultaneous release the release and compression can be delayed from eight to ten degrees as compared with the results obtained by the usual construction of a single connection to the valve or valves from the link-block, the magnitude of the delay in release and compression thus secured depending on the amount of separation of the link-block pin-centers.

The principle of my invention is capable of application to practically all the known types of valve systems and reversing-gears, and in the present application I have illustrated the same in connection with the well-known Stephenson link and valve systems of the "V-valve" and "piston" types.

Referring to the drawings, Figure 1 is an elevational view, partly in section, of so much of the valve mechanism and reversing-gear of a vertical steam-engine as is necessary to illustrate the principle and construction of my invention, the valve mechanism shown being of the piston type. Fig. 2 is a vertical sectional view through the valve-chest shown

in Fig. 1 in the plane of the inner group of 55 valves. Fig. 3 is a view similar to Fig. 1, showing a V-valve mechanism and also illustrating a modification in the connections between the valve-stems and the eccentric-pins of the link-block designed to accommodate a 60 relatively wide separation of the valve-stems. Fig. 4 is a vertical sectional view through the cylinder and valve-chest in a plane at right angles to the plane of Figs. 1 and 2, and more particularly illustrating the differential lap 65 applied to the two sets of valves. Fig. 5 is a cross-sectional view on the line 5 5 of Fig. 4. Fig. 6 is a vertical sectional view on the line 6 6 of Fig. 3. Fig. 7 is a similar sectional view through the cylinder and valve-chest on 70 the line 7 7 of Fig. 3.

Referring to Figs. 1, 2, 4, and 5 and describing first those parts which are common and well known in steam-engine construction, 10 and 11 designate, respectively, the 75 forward and backing eccentrics, mounted on the crank-shaft in the usual manner and connected through eccentric-straps 12 and 13 and rods 14 and 15, respectively, with the opposite ends of the link 16. This link is the 80 Stephenson or shifting link supported upon the eccentric-rods 14 and 15 and shiftable to effect reversal and variation of stroke from the tumbling-shaft 21 by means of a pair of bars 17, connected thereto and adjustably 85 secured at their outer ends to a block 18, slidably mounted in a frame 19, carried on the free end of arm 20, keyed on the tumbling-shaft 21, said shaft having another 90 arm 22, which is connected by a link 23 to the usual engineer's reversing-lever. (Not shown.) Mounted upon and slidably relatively to the link 16 is a link-block 24. 25 designates an engine-cylinder, 26 a piston therein, and 27 the piston-rod, having the 95 usual connections to the driving-shaft. (Not shown.) 28 represents the valve-chest, located alongside the cylinder and having the usual steam-pipe 29 and exhaust-pipe 30. In the valve-chest are two series or groups of 100 piston-valves, the inner group of three valves (shown in Figs. 2 and 4) being designated by 31 and the outer group consisting of a pair of valves designated by 32. The opposite valve-bodies of the two groups, 105 which lie in longitudinal alinement at opposite ends of the chest, respectively, are connected by rods 33 and 34, respectively, the

series of rods 33 being interconnected within the valve-chest by a bar or key 35 or equivalent bridgework, so as to move in unison, and the pair of rods 34 being similarly connected by a bar or key 36. Valve-stems 37 and 38, connected to the inner and outer groups of valves, respectively, extend through suitable stuffing-boxes in the lower end of the valve-chest.

10 In the above-described valve mechanisms the three valves at each end of the inner group and the two valves at each end of the outer group work together to constitute, in effect, a single valve for the control of the motive fluid. While the piston type of valve is old and well known in practice and possesses both advantages and disadvantages as compared with the D type of slide-valve, yet the employment of a plurality of piston-
15 valves in each group has the still further feature of increased linear extent of opening at the periods of admission and cut off, as compared with the single valve-body, and is also less liable to derangement, leakage, or
20 sticking, owing to inequality of contraction and expansion. One feature of my invention, therefore, resides in the type of valve construction shown and described, which is of course capable of general application and
25 beneficial use in an engine employing any kind or type of valve-motion mechanism.

Considering now those features wherein the more important part of my invention resides, it will be observed that the link-block 35 24 carries a pair of pins 39 and 40, (shown in full lines in Fig. 6 and in dotted lines in Figs. 1 and 3,) the centers of these pins being spaced apart through a considerable interval longitudinally of the link-block. From the pin 39 there extends a connecting-rod 41 to a cross-head 42, slidably mounted in a guide 43, which cross-head is connected at its upper end to the lower end of the valve-stem 38. Similarly the link-block pin 40 is connected
40 by connecting-rod 42 to the lower end of the valve-stem 37, a portion of said connecting-rod being slidably mounted in a guide 43, whereby the link-block itself is held against movement relatively to the link, except when
45 the latter is adjusted thereto for purposes of reversal or variation of stroke.

The position of the link and its operating devices, represented by full lines, is the forward or "ahead" position, and it will be observed that by reason of the fact that the link-block pin 39, to which is connected the outer series of valves 32, is nearer the driving end of the link than is the link-pin 40, connected to the valves 31, the former series of
55 valves will have a travel greater than the latter and later with respect to the crank. Consequently if the valves of both sets had the same amount of outside lap the valves of the inner set, having the lesser travel and
60 earlier motion, would cut off earlier than the

valves of the outer set. In order to overcome this and cause both sets of valves to cut off simultaneously, I provide additional outside lap on the outer set of valves, as more clearly indicated in Fig. 4. Similarly 70 if both sets of valves had the same inside lap the inner set would release earlier than the outer set, and in order to produce a simultaneous release I add enough inside lap to the inner set of valves to effect such simultaneous release of both sets. This use of differential lap may be illustrated by an example giving concrete dimensions, as follows: Assume that the travel of the outer set of valves, having the greater and later motion, 80 is six inches, and that with an outside lap of one and one-half inches they will cut off at one hundred and twenty degrees or three-fourths of stroke, and with inside edges line and line they will release and compress at 85 one hundred and fifty degrees or fifteen-sixteenths of stroke. The travel of the second or inner set of valves driving from the pin 40, having the lesser and earlier motion with respect to the crank-pin, would be five and one-eighth inches, and having an outside lap of one and one-half inches they will cut off steam at one hundred and five degrees or five-eighths of stroke. Now in order to make the valves with the longer or six-inch 90 travel cut off at five-eighths stroke, about nine-sixteenths outside lap would be added, making a total outside lap of two and one-sixteenth inches. The valves having the lesser travel with inside edges line and line 100 will release and compress at one hundred and forty-two and one-half degrees or nine-tenths of stroke. In order to make these valves release simultaneously with the other set of greater travel, approximately one-fourth 105 inch inside lap must be added. With these dimensions and conditions when the link-block travel is further reduced or the link "hooked up" the valves would cut off together at ninety degrees or one-half of stroke 110 and release at one hundred and forty-two and one-half degrees or nine-tenths of stroke simultaneously. With this arrangement there follows steam lead or preadmission with only one set of valves, the second set opening for steam when the crank has passed the dead-point about fifteen degrees or one-sixtieth of the stroke. At this point the piston has not attained any considerable velocity, so that the opening from one set of valves is ample, and the delayed opening of the second set is not objectionable. The cut-off, as above stated, is simultaneous 120 with both sets of valves when running right-handed or forward, and release is likewise so, 125 which is very essential in a good valve-gear. Compression is timed by the valves having the greater travel alone, which is no objection practically. With this arrangement steam-distribution in the left-hand or backing mo- 130

tion is not quite as perfect as in the right-handed or forward motion, but is ample for practical purposes in all engines, such as marine and locomotive engines, wherein the amount of work required of the engine in the backing motion is practically negligible so far as questions of economy are concerned.

Figs. 3, 6, and 7 show the invention embodied in a valve mechanism of the ordinary D type. In this case a pair of D-valves are employed, located side by side and operating over a common valve-seat. Referring to these figures, 44 designates the valve-seat, provided with the usual inlet-ports 45, leading to opposite ends of the cylinder, and the intermediate exhaust-port 46. In this valve-seat are slidably mounted side by side a pair of D-valves 47 and 48, respectively. These valves are shown side by side in Fig. 3 and separately in Figs. 6 and 7. The valve 47 has a stem 49 extending through a suitable stuffing-box in the lower end of the valve-chest, such stem having a loose sliding-block connection with one end of the free cross-head 50, to the opposite end of which is similarly connected the valve-stem 51 of the valve 48. To the cross-head 50 at points between the connections of the valve-stems thereto are pivotally connected a pair of connecting-rods 52 and 53, the former traveling in a fixed guide 54 and being connected at its lower end to the pin 40 of the link-block, and the connecting-rod 53 being similarly connected at its lower end to the pin 39. By this mechanism a change of the motion of the different valves similar in character to that effected by the apparatus already described is effected, such mechanism further permitting a wider separation of the valve-stems and a less separation of the link-block pin-centers. As will be observed by a comparison of the two valves 47 and 48, as shown in Figs. 3, 6, and 7, the valve 48, having the greater travel and later motion, is provided with additional outside lap relatively to its companion valve in order to effect simultaneous cut off when the engine is running in forward or ahead direction, while similarly the valve 47, having the lesser travel and earlier motion, is provided with a slight additional inside lap in order to delay release and effect the later operation simultaneously with the valve 48.

It is evident that the free cross-head con-

nexion last described might be employed in connection with two groups of piston-valves, and also that the latter might be substituted for the D-valves of Fig. 3, if desired, with the same beneficial results.

I claim—

1. In a fluid-pressure motor, the combination with a cylinder and valve-chest having a pair of independently-movable valves, of a reversing-gear including a rocking lever and a block slideable relatively thereto, and valve-actuating rods connected to said block at separated points longitudinally thereon. 60

2. In a fluid-pressure motor, the combination with a cylinder and valve-chest having a pair of independently-movable valves, of a reversing-gear including a link and link-block slideable relatively thereto, the latter having two different pivots separated in the direction of motion of the block relatively to the link, and connections from said pivots to 75 said valves. 70

3. In a fluid-pressure motor, the combination with a cylinder and valve-chest and a reversing-gear including a rocking lever and a block slideable relatively thereto, of a pair of independently-movable groups of piston-valves in said valve-chest, each group comprising a plurality of connected and similarly operating valves, and independent connections from said groups of valves to separated 85 points on said block. 80

4. In a fluid-pressure motor, the combination with a cylinder and valve-chest, of independently-movable valves or sets of valves each having admission and exhaust functions and provided with different amounts of steam and exhaust laps, and means for imparting to said valves independent time motions. 90

5. In a fluid-pressure motor, the combination with a cylinder and valve-chest, of independently-movable valves or sets of valves each having admission and exhaust functions and provided with different amounts of steam and exhaust laps, a link, link-block, 100 and valve-actuating means connected to said link-block at longitudinally-separated points thereon. 95

CHARLES HAMMEN.
